(57) **CLAIM**

The ornamental design for clipper handles, as shown and described.

DESCRIPTION

FIG. 1 is a perspective view of the clipper handles showing our new design, the handles being shown on a clipper in the closed configuration for purposes of illustrating use, with other clipper components being shown in dotted lines for purposes of illustrating the environment and forming no part of the claimed design;

FIG. 2 is a front view thereof;

FIG. 3 is a rear view thereof;

FIG. 4 is a left side elevation thereof;

FIG. 5 is a right side elevation thereof;

FIG. 6 is a top view thereof;

FIG. 7 is a bottom view thereof;

FIG. 8 is a perspective view of the clipper handles showing our new design, the handles being shown on a clipper in the open configuration for purposes of illustrating use, with other clipper components being shown in dotted lines for purposes of illustrating the environment and forming no part of the claimed design;

FIG. 9 is a front view thereof;

FIG. 10 is a rear view thereof;

FIG. 11 is a left side elevation thereof;

FIG. 12 is a right side elevation thereof;

FIG. 13 is a top view thereof; and,

FIG. 14 is a bottom view thereof.
